CLAIM

The ornamental design for a display screen or portion thereof with graphical user interface, as shown and described.

DESCRIPTION

FIG. 1 illustrates a front view of a display screen or portion thereof with a graphical user interface (GUI), wherein parts of the GUI are shown in broken lines for illustrative purposes;

FIG. 2 illustrates a front view of a second embodiment of the GUI set forth in FIG. 1;

FIG. 3 illustrates a front view of a third embodiment of the GUI set forth in FIG. 1;

FIG. 4 illustrates a front view of a fourth embodiment of the GUI set forth in FIG. 1;

FIG. 5 illustrates a front view of the fifth embodiment of the GUI set forth in FIG. 1;

FIG. 6 illustrates a front view of the sixth embodiment of the GUI set forth in FIG. 1; and,

FIG. 7 illustrates a front view of the seventh embodiment of the GUI set forth in FIG. 1.

In these drawings, the solid lines illustrate the claimed ornamental design, whereas the broken lines illustrate environmental features, such as the display screen or the device that depicts ornamental design, that form no part of the claimed ornamental design of the subject embodiment. The graphical user interface may transition between the images shown in FIGS. 1-7. However, the process or period in which an image transitions into another image forms no part of the claimed design.
